DES. 2240

Sidney Smith of Greenfield Mass
Letters Patent No. 2240. Dated Jan'y 9, 1866.
Design for the Plates of a Stove.

The schedule referred to in these letters Patent and making part of the same.

To all whom it may concern,

Be it known that of Sidney Smith
of Greenfield in the County of Franklin and State of
Massachusetts have originated a new design for stove
plates of which the following is a full, clear and exact
descriptive reference being had to the accompanying
photographic representation of the same.

The figure represents a cook stove with elevated
over, the ornamental design being upon the front
panels and upon the over doors.

The panels A, are formed by cymatium molding
having a bead on its inner edge. The panel is square
at the bottom, and semi-elliptical at the top.

In the centre of the panel A, is a vase, standing
upon bracket, supported by bunches of grapes with
grape leaves, and surmounted by trifoliate pendants.

The bracket B, has a semi-hexagonal table, the
edge of which forms a cymatium molding with a bead
similar to the molding of the panel. Below are interlaced
grape leaves and pendent. Below the leaves is a cluster
of grapes.

The vase C, stands upon a broad flat base and
presents in profile the figure of the Cyma Recta. At the base
of the body is a simple and a beaded fillet, and at the
lower part of the body are eggs surrounded by cavello-over
molding.

2

OES. 2240

The cover of the vase has a thumbed edge, and
canopy shaped above with an ornamented frieze

Above the vase is a trefoil-cavetto-ovolo molding
D. with pendants from the lower foils, which just enclose
the edges of the cover. The centre of the middle foil is
ornamented with an enclosed fillet and at the junction
of the foils are the ordinary scroll buttons.

Having described my design what claim is the panel, bracket, vase and trefoils as figured.
and described. -- Humphrey Stevens Petrusso.
